Attorney

UNITED STATES PATENT OFFICE.

JOHN S. BARNES, OF DETROIT, MICHIGAN.

WIRE FABRIC.

1,339,541.

Specification of Letters Patent. Patented May 11, 1920.

Application filed October 3, 1918. Serial No. 256,673.

To all whom it may concern:

Be it known that I, JOHN S. BARNES, citizen of the United States, residing at Detroit, county of Wayne, State of Michigan, have invented a certain new and useful Improvement in Wire Fabric, and declare the following to be a full, clear, and exact description of the same, such as will enable others skilled in the art to which it pertains 10 to make and use the same, reference being had to the accompanying drawings, which form a part of this specification.

My invention relates to a wire fabric shown in the accompanying drawings and 15 more particularly set forth in the following specification and claims.

One of the objects of this invention is to produce a wire fabric of simple and inexpensive construction in which both the 20 transverse and lateral wires are continuous throughout the length of the fabric, the construction being such that by the use of a machine which will form the subject-matter of another application for Letters Patent, the fabric may be produced with great 25 rapidity and at a minimum cost of manufacture.

While the fabric thus produced is adapted for a wide range of purposes it may be employed to reinforce trench walls, construct 30 knock-down packages, chicken houses, fences, form waste-paper incinerators, or the like.

With the foregoing and other objects in view, which will appear as the description 35 proceeds, the invention resides in the combination and arrangement of parts and in the details of construction hereinafter described and claimed, it being understood however that changes may be made in the precise 40 embodiment of the invention herein disclosed without departing from the spirit of the same.

In the accompanying drawings forming part of this specification:—

45 Figure 1 is a side elevation of a section of the fabric.

Fig. 2 is an enlarged detail view showing the construction of the interlocking lateral wires or strips.

Fig. 3 is a cross-sectional view on line 50 3—3 of Fig. 2.

Fig. 4 is a vertical sectional view on line 4—4 of Fig. 2.

Fig. 5 is a detail sectional elevation of a modification, showing the pickets bent to 55 interlock with the lateral wires to provide against displacement.

Referring now to the letters of reference placed upon the drawings:—

A denotes a continuous strand of wire 60 constructed with return bends spaced apart and forming the vertical members or pickets of the fabric.

B indicates a continuous flattened lateral wire or strip, notched on each edge as indicated at B¹ to receive the pickets.

C designates a relatively narrow flattened lateral wire or strip coöperating with the wire B to engage the respective pickets formed by the wire A. 70

The wires B and C are each provided with opposing indentations D to receive the pickets, as indicated in Fig. 3; and between adjacent pickets the edges of the wire B are bent to overlap the edges of the wire C as 75 shown in Fig. 4, thereby making the wires B and C in effect a single lateral unit engaging the pickets.

To provide against displacement of the lateral wires with respect to the pickets, 80 the latter may be indented as shown at E in Fig. 5, thereby securing the parts in fixed relation to each other.

Instead of forming the pickets by bending a continuous wire strand in alternate reverse directions, separate pickets may be employed held by a plurality of pairs of the coöperating lateral members previously described. 85

Having thus described my invention, what 90 I claim is:—

1. A wire fabric comprising a continuous strand of wire having return bends spaced apart to form pickets, said pickets being indented at spaced intervals to receive intersecting members, and a plurality of intersecting members consisting of pairs of continuous strips also indented at intervals to 95

receive the pickets formed by the strand of wire, one member of each pair of intersecting strips overlapping the edges of the other intersecting member between said pickets to form a single intersecting unit.

2. A fabric comprising a plurality of pickets spaced apart and severally indented at spaced intervals to receive a pair of overlapping intersecting members; and a plurality of coöoperating pairs of intersecting members spaced apart having opposing in-

dentations to receive the indented portions of the pickets, the edges of one member of each pair of intersecting members being bent between the pickets to overlap the edges of the cooperating intersecting member. 15

In testimony whereof, I sign this specification in the presence of two witnesses.

JOHN S. BARNES.

Witnesses:

S. E. THOMAS,
JOHN CONSIDINE, Jr.
